COMBINATION CLOTHES RACK AND
LOCKER

Russell V. Polen, Dayton, Ohio, assignor, by mesne assignments, to Lyon Metal Products, Incorporated, Aurora, Ill., a corporation of Illinois

Application July 17, 1937, Serial No. 154,265
Renewed July 6, 1939

9 Claims. (Cl. 312—106)

This invention relates to clothes racks and particularly to a combined clothes rack and locker device.

An object of my invention is to provide an improved combined clothes rack and locker device of unitary construction.

Another object of my invention is to provide a combined clothes rack and locker capable of receiving and independently locking the clothes of a plurality of users that is compact and will therefore occupy a comparatively small amount of floor space.

A further object of my invention is to provide an improved compact combined clothes rack and locker device that is constructed entirely of sheet metal stampings or punchings.

Yet another object of the invention is to provide a combined locker and coat hanging rack wherein means is provided whereby a person may hang his coat upon a hanger and may lock his hat in one of a number of lockers and wherein means is provided for preventing the removal of the coat from the hanger unless the locker is unlocked, whereby to prevent theft of the coat and whereby a hung coat is always identified with a particular locker.

A still further object of my invention is to provide a combined clothes rack and locker device for use by a plurality of persons and in which device the clothes such as topcoats or overcoats of each individual user is locked to the individual's locker containing his or her hat or other small items to thereby render all the removed wearing apparel of each user substantially theft proof.

In carrying out the foregoing objects it is a still further and more specific object of my invention to provide a combined clothes rack and locker device in which the lockers thereof are reticulated for air circulation therethrough and in which the clothes supported by the rack are exposed for quick drying purposes.

Further objects and advantages of the present invention will be apparent from the following description, reference being had to the accompanying drawings, wherein a preferred form of the present invention is clearly shown.

In the drawings:

Fig. 1 is a perspective view of a combined clothes rack and locker device constructed in accordance with the present invention;

Fig. 2 is a fragmentary vertical sectional view through the locker portion of the device shown in Fig. 1 and is taken on the line 2—2 of Fig. 4;

Fig. 3 is a fragmentary horizontal sectional view

through the device shown in Fig. 1 and is taken on the line 3—3 of Fig. 4; and

Fig. 4 is a vertical section through the locker portion of the device shown in Fig. 1 and is taken on the line 4—4 of Fig. 2.

Referring to the drawings, for illustrating the invention, I have shown in Fig. 1 thereof a unitary combined clothes rack and locker device generally represented by the reference character 10. The device 10 comprises a base 11 having end upright U-shaped iron members 12 and 13 secured thereto by a pair of metal plates 14. Each plate 14 is welded or otherwise rigidly secured to base 11 and one plate 14 is secured to the upright iron member 12 by bolts or rivets 15 while the other plate is similarly secured to the upright 13. Metal braces 16 extend at an angle to each of the uprights 12 and 13 and have one end secured thereto by bolts or rivets 17 and have the other end secured by bolts or rivets 18 to base 11. The standard formed by the elements 11, 12, 13, 14, and 16 is adapted to support a preferably horizontally elongated box-like structure generally represented by the reference character 20. This box-like structure 20 forms a locker portion of the device 10 and is constructed of a plurality of sheet metal plates secured together and arranged to provide a plurality of separated compartments or lockers 21 (see Figs. 2, 3 and 4). The elongated box-like structure or locker portion 20 of the device 10 rests upon and is supported by the uprights 12 and 13. A metal plate 23 is secured to the upright 13 by bolts or rivets 24 and a second similarly shaped plate 25 at the other end of the standard is secured to the upright 12 by bolts or rivets 26. The plates 23 and 25 fit under the ends of the box-like portion 20 of device 10 and are secured thereto by bolts or rivets 28 (see Fig. 4) to thereby rigidly hold the portion 20 of device 10 upon the upright supports 12 and 13 to form 40 a unitary structure. Angularly disposed metal braces 29 and 31 have one end secured to uprights 12 and 13 by bolts or rivets 32 and have their other ends secured by bolts or rivets 33 (see Fig. 4) to the bottom wall of the box-like or locker portion 20 of the device 10. It will be noted that the upright U-shaped iron members 12 and 13 and the angularly disposed T-shaped braces 16, 29 and 31 are located at the longitudinal vertical center of the unitary device 10 and that the base 50 11, plates 14, 23 and 25 as well as the box-like or locker portion 20 extend outwardly a considerable distance from the center of the standard. The space below the locker portion 20 of device 10 provides a suitable shielded or sheltered clothes

storage space. Therefore I utilize this space as a clothes rack and in order to hang clothes in the space provided on each side of the uprights 12 and 13 I have provided elongated means herein shown as a relatively long rod 35 extending substantially coextensive with the horizontal series of lockers and preferably from plate 23 to plate 25 on each side of the angularly disposed metal braces 29 and 31. Caps 36 threaded upon 10 threaded end portions of rod 35, protruding through plates 23 and 25 (see Fig. 4), secure the rods 35 in position on the device 10. These rods 35 form clothes supporting means or racks below the box portion 20 of device 10 and support a 15 plurality of hangers or coat supporting means 38 having a closed ring portion 39 encircling the rod (see Fig. 2). Each hanger 38 has a chain 41 secured thereto by a closed ring portion or element 42 and a lock 43. The purpose of permanently 20 securing the hangers 38 to rods 35 and chains 41 to the hangers will become apparent hereafter.

By referring now to Figs. 2, 3 and 4 it will be seen that the plurality of compartments or lockers 21 provided in locker portion 20 of the unitary 25 device 10 are formed by a plurality of vertically disposed sheet metal plate members 51 and 52 and by a plurality of horizontally disposed sheet metal plate members 53 and 54 secured together by bolts or rivets 55. It will be noted that the 30 vertical sheet metal plate members 51 form continuous or solid side walls for the compartments 21 and that the longitudinally extending vertical sheet metal plate member 52 is provided with a plurality of openings 56 therein to thereby provide reticulated partitioning end walls of the vertically disposed horizontally aligned compartments 21. It is also to be noted that the horizontally disposed sheet metal plate members 53 form the closed top and bottom walls of the locker 35 section 20 of device 10 and that the intermediate sheet metal plate members 54 form partitioning walls between the vertically aligned compartments 21. Therefore the locker section 20 of device 10 comprises a plurality of rows of vertically aligned and a plurality of rows of horizontally aligned lockers or compartments 21. In the structure disclosed ten lockers or compartments 21 are provided on each side of the device 10 to thus provide a device that can be used by twenty 40 employees or individuals. However, it is to be understood that a device constructed in accordance with the present disclosure and containing any desired number of lockers and hangers may be provided without departing from the spirit of 45 my invention. Each locker 21 has its open front closed by a door 61 comprising a frame 62 and an intermediate wire mesh or the like portion 63 welded or otherwise suitably secured to the door frame (see Fig. 2). Each frame 62 of door 61 has 50 a slot or hasp portion cut or formed therein for receiving a staple portion 65 of a metal bracket 66 secured inwardly of the lockers 21 and projecting outwardly therefrom (see Figs. 2 and 3).

In the use of the device 10 by employees each 55 individual is assigned a locker number and a corresponding clothes hanger number and each upon removing their topcoat, raincoat or overcoat hang same on their assigned clothes hanger. The padlock 43 is unlocked and removed from 60 the hanger and the padlock or free end of chain 41 is passed through a sleeve of their coat. The individual's hat is removed and placed in the assigned locker 21 and the locker door 61 is closed. Then the padlock 43 secured to the 65 free end of chain 41 is locked to the staple por-

tion 65 of bracket 66, which protrudes outwardly from locker door 61 when the door is closed. Thus the individual's coat is locked to the non-removable hanger 38 by the chain 41 and door 61 of the individual's locker 21 is also locked by the lock 43. Such an arrangement is illustrated in Fig. 1 of the drawings and from this showing the operations necessary for using the device 10 are obvious. The perforated vertical partition 52 of the locker 21 and the perforated door or wire mesh fronts thereof provide air circulation between the interior of the compartments 21 and the air exteriorly of the device. Thus all wearing apparel removed by the individual and locked to or within the combined clothes rack and locker device 10 is exposed to the air within the room in which the device is locked and will be dried quickly should they be wet when removed from the individuals. The ventilation of the lockers or compartments 21 also permits proper storage 15 of food products such as the user's lunch or the like.

It will be seen from the foregoing that I have provided an improved combined clothes rack and locker structure which is constructed entirely of 20 steel and sheet metal punchings or stampings to thereby reduce manufacturing costs thereof and to form a rigid, strong and durable unitary construction. The improved device while accommodating the clothes of a plurality of persons 25 and locking same thereto in a theft proof manner occupies a minimum amount of floor space. My improved combined device eliminates the necessity of providing a plurality of clothes closets and separate lockers for a plurality of 30 employees or individuals and the locking of the clothes in the manner described prevents individuals accidentally removing the wrong wearing apparel from the device. A device constructed in accordance with my invention is particularly 35 useful in manufacturing plants and the like where to minimize the floor space to be occupied by such devices is of high importance.

While the form of embodiment of the invention as herein disclosed, constitutes a preferred 40 form, it is to be understood that other forms might be adopted, all coming within the scope 45 of the claims which follow.

What is claimed is as follows:

1. A unitary structure forming a combined 50 clothes rack and locker device comprising in combination, a base, a pair of spaced apart members secured to said base and supporting means extending upwardly therefrom, a box-like element permanently attached to and supported 55 upon said supporting means, said box-like element extending outwardly away from said supporting means and forming a sheltered space on each side thereof intermediate their tops and said base, means disposed in the upper portion 60 of each of the spaces below said box-like element and extending substantially throughout the length thereof supporting a plurality of hangers, said hangers each being movable along the length of their supports and constructed and arranged 65 to prevent removal therefrom, said box-like element comprising a plurality of walls dividing same into a plurality of rows of locker compartments each having a door opening and a door for closing the opening, each of said plural- 70 ity of hangers having a continuous flexible member associated therewith, each of said flexible members having one end permanently secured to its associated hanger and adapted to be ex- 75 tended through a sleeve of a coat or the like 75

- adapted to be supported on the hanger, and the free end of each of said flexible members having a lock permanently secured thereto and adapted to be removably attached to a portion of said 5 box-like element for securing the coat to said structure and for locking the locker compartment door.
2. A unitary structure forming a combined clothes rack and locker device comprising in combination, a base, a pair of spaced apart members secured to said base and extending upwardly therefrom, a box-like element permanently attached to and supported upon said members, said box-like element extending outwardly away 10 from said upright members and forming a sheltered space on each side thereof intermediate their tops and said base, means disposed in the upper portion of each of the spaces below said box-like element and extending substantially throughout the length thereof supporting a plurality of hangers, said hangers each being movable along the length of their supports and constructed and arranged to prevent removal therefrom, said box-like element comprising a 15 plurality of walls dividing same into a plurality of horizontally aligned and a plurality of vertically aligned rows of locker compartments each having a door opening and a door for closing the opening, the end walls of said horizontally aligned 20 locker compartments being reticulated for circulation of air therebetween and therethrough, each of said plurality of hangers having a chain associated therewith, each of said chains having one end permanently secured to its associated 25 hanger and adapted to be extended through a sleeve of a coat or the like adapted to be supported on the hanger, and the free end of each of said chains having a lock permanently secured thereto and adapted to be removably attached 30 to a portion of said box-like element for securing the coat to said structure and for locking the locker compartment door.
3. A unitary structure providing a combined clothes rack and locker device comprising in combination, a standard portion and a box-like portion supported thereupon, said box-like portion of said device being elongated and forming a sheltered space intermediate the top and bottom of said standard portion, said box-like portion including a plurality of walls dividing same into a row of locker compartments each having a door opening and a door for closing the opening, a support member secured to said device in the upper part of the sheltered space below the box-like portion thereof and having a plurality of coat or the like supporting units thereon, certain of said coat or the like supporting units including a hanger and a flexible element adapted to be extended through a sleeve or opening of a 50 garment supported on said hanger, and an end of said flexible element being constructed and arranged to receive a lock adapted to be attached to a part of said box-like portion of said device for locking a locker compartment door and for locking the garment against removal from said structure.
4. A unitary structure forming a combined clothes rack and locker comprising in combination a base, supporting means extending upwardly therefrom, a series of lockers mounted on said supporting means, said lockers extending outwardly to form a sheltered space therebeneath, means disposed in such space below said locker elements and extending substantially throughout the length thereof supporting a plurality of 55 hangers, each of said hangers being movable along the length of said supporting means and being non-detachable therefrom, each of said lockers having a door opening, and a door for closing the same, each of said plurality of hangers having a flexible elongated member associated therewith, each said flexible member having one end permanently secured to its hanger and adapted to be extended through the sleeve of a coat or the like hung on the hanger, and the free end of each of said flexible members having means adapted to engage with any one of said lockers and being constructed and arranged whereby upon the closing and locking of the door of said locker said end of said flexible member will be irremovably connected thereto.
5. A combined locker and coat hanger comprising means forming an elongated, longitudinally disposed series of lockers, a door for each locker and having means for locking the door 20 whereby relatively small articles may be retained in each of said lockers when the door is locked, and means disposed adjacent to and extending substantially coextensively with said series of lockers supporting a plurality of coat hangers, 25 said means and said hangers being constructed and arranged to permit said hangers individually to be moved along the length of said supporting means while preventing removal of said hangers from said supporting means, each of said hangers having an elongated, flexible member irremovably attached thereto and adapted to be extended through the sleeve of a coat or the like and having an end portion provided with locking means adapted to engage the locking means of 30 the door whereby to lock the door and to lock the flexible member to the locker.
6. A combined locker and coat hanger comprising means forming an elongated, longitudinally disposed series of lockers, each locker having a lockable closure whereby relatively small articles may be placed in each of said lockers and retained therein by locking the closures therefor, and means disposed substantially coextensively with said elongated horizontal series 40 of lockers supporting a plurality of coat hangers, said means and said hangers being constructed and arranged to permit said hangers individually to be moved along the length of said supporting means and constructed and arranged to prevent removal of said hangers from said supporting means, each of said plurality of hangers having an elongated flexible member irremovably associated therewith and adapted to be extended 45 through the sleeve of a coat or the like, the free end of each of said flexible members having a padlock permanently secured thereto and adapted to be irremovably attached to a locker and its closure for locking the closure of said locker and whereby said padlock, when in position in locking the closure of a particular locker, will likewise lock the particular hanger and the coat hung thereon, irremovably to said locker.
7. A combined locker and coat hanger comprising means forming an elongated, longitudinally disposed series of lockers, each locker having a lockable closure whereby relatively small articles may be placed in each of said lockers and retained therein by locking the closures therefor, and means disposed substantially coextensively with said elongated horizontal series of lockers supporting a plurality of coat hangers, said means and said hangers being constructed and arranged to permit said hangers individually to be moved along the length of said supporting 55 means.

means and constructed and arranged to prevent removal of said hangers from said supporting means, each of said plurality of hangers having an elongated, flexible member irremovably connected thereto and adapted to be extended through the sleeve of a coat or the like, the free end of each of said flexible members having means adapted to be associated with the closure of a locker, whereby, when the closure of said locker is locked, the free end of such flexible member will likewise be locked to such locker.

8. In combination, an elongated series of lockers, each locker having a lockable closure, elongated supporting means disposed substantially parallel to said elongated series of lockers and substantially coextensively therewith, means for irremovably supporting a plurality of coat hangers on said supporting means, said means permitting said coat hangers to shift lengthwise of said supporting means, each of said coat hangers having fixed thereto one portion of an elongated member adapted to be passed through the sleeve of a coat or the like supported on the hanger, a spaced portion of said elongated member having means adapted to be irremovably attached to a particular locker when the closure of said lock-

er is locked but detachable from said locker when the closure of said locker is unlocked or opened.

9. A clothes rack comprising a series of individual lockers, each locker having a lockable door, said series extending in both horizontal and vertical directions, means disposed below and adjacent said lockers and substantially parallel to and substantially coextensive with the horizontally disposed tier of said lockers, said means being adapted shiftably and non-detachably to support a series of coat hangers, whereby each coat hanger may be shifted directly under any locker or whereby one or more coat hangers may be shiftably disposed beneath or adjacent to any one of said lockers, each coat hanger having elongated means irremovably attached thereto and adapted to be passed through the sleeve of a coat suspended on said hanger, the free portion of said elongated means having means adapted to be associated with a closing means of any locker, whereby, when said closing means is locked in closed position, the coat suspended from said hanger will be irremovably associated with such closed locker.

RUSSELL V. POLEN. 25
